UNITED STATES PATENT OFFICE.

HUBERT F. PROBERT, OF CHICAGO, ILLINOIS.

MEANS FOR TRANSMITTING POWER AND REVERSING ITS MOTION.

SPECIFICATION forming part of Letters Patent No. 624,973, dated May 16, 1899.

Application filed April 8, 1897. Serial No. 631,273. (No model.)

To all whom it may concern:

Be it known that I, HUBERT F. PROBERT, a citizen of the United States, residing at Chicago, in the county of Cook and State of Illinois, have invented certain new and useful Improvements in Means for Transmitting Power and Reversing its Motion, of which the following is a full, clear, and exact specification.

My invention relates more particularly to reversing-gears for boat-propellers, whereby the continuous movement of the motor-shaft in one direction may be converted or reversed to the opposite direction as applied to the propeller, thus avoiding the necessity of stopping and reversing the motor when it is desired to rotate the propeller in the opposite direction.

My invention has especial reference to a reversing-gear in which the motor-shaft and propeller-shaft have direct and convertible gear connections capable of being alternately thrown into and out of operation; and my invention has for its primary object to cause a single movement of the reversing lever or handle in one direction to disconnect the direct gear and connect the convertible gear, and vice versa.

Another object of my invention is to utilize the resistance against the propeller for forcing the direct gears together.

A still further object is to provide means for adjusting the throw of the reversing lever or handle, whereby its angle with reference to the horizontal may be varied when at the limit of either extremity of its throw, and thus be capable of being adjusted to suit the convenience of the engineer.

With these ends in view my invention consists in certain features of novelty in the construction, combination, and arrangement of parts by which the said objects and certain other objects hereinafter appearing are attained, all as fully described with reference to the accompanying drawings, and more particularly pointed out in the claims.

In the said drawings, Figure 1 is a vertical longitudinal sectional view of the stern end of a boat provided with an engine and propeller equipped with my improved reversing-gear. Fig. 2 is an enlarged side elevation of the reversing-gear, partly broken away and

showing the parts in the condition they assume when the direct gears are in engagement, the shaft being sectioned on line 2-2, 55 Fig. 1. Fig. 3 is a view taken at right angles to Fig. 2, showing the casing in vertical section on the line 3-3, Fig. 2, the direct gears being in engagement. Fig. 4 is a similar view showing the convertible gears in operation 60 and the direct gears out of engagement, the section in this figure being also taken on the line 3-3, Fig. 2, and extended through the internal parts. Fig. 5 is a plan view of the lower half of the casing. Fig. 6 is a perspective view looking at the outer side of one of the bevel gears or cones hereinafter described, and Fig. 7 is a face view of the inclines on one side of the interior of the casing.

As before mentioned, my invention is more particularly adapted for use in connection with propellers; but it will of course be understood, nevertheless, that the same is equally appropriate for any mechanism where it is desired that the continuous movement of a 75 rotating shaft or member shall be converted into rotary movement in some other member turning to the right or to the left.

In applying my invention to a boat-propeller the propeller 1 is mounted upon the 80 outer end of a propeller-shaft 2, which in turn is journaled in a suitable stuffing-box in the stern-block 4 of the boat 5 in the ordinary or any suitable manner. The engine or motor, which is here shown as a gas-engine, is so 85 mounted that its driving-shaft 6 will be in alinement with the propeller-shaft 2 and is rigidly held in place by the parts of the engine connected therewith or by other suitable means, while the propeller-shaft is capable 90 of limited longitudinal movement. Mounted upon the end of each of these shafts 2 6 is a clutch member 7 8, respectively, which, as more clearly shown in Figs. 3 and 4, are provided with ratchet-teeth so formed that when 95 brought together the rotation of the engine-shaft in one direction will be imparted directly to the propeller-shaft 2 in the same direction. These clutch members 7 8 constitute the direct gears herein referred to and are caused to engage and disengage by the longitudinal movement of the propeller-shaft 2, which is effected by mechanism presently to be described. Also secured to each of the

shafts 2 6 is a conical or beveled gear 9 10, which for the sake of convenience of construction may be formed on the clutch members 7 8, respectively. These gears 9 10 are arranged with their conical or beveled sides opposed, and the one on the propeller-shaft 2 approaches and recedes from the other as the clutch members 7 8 are moved into and out of engagement. The clutch members 7 8 are forced out of engagement when it is desired to reverse the movement of the propeller-shaft 2 by a conical or beveled gear 11, which is arranged with its axis at right angles to the shafts 2 6 and when forced in between the gears 9 10 serves not only to separate the clutches 7 8 but to communicate the motion of the gear 10 to the gear 9 and to convert such motion to the opposite direction to that in which the motor-shaft 6 rotates. These gears 9 10 11 might of course be in the form of ordinary bevel-pinions and the same general result accomplished; but in order that the propeller may be reversed while the engine is traveling at high speed and all parts may be caused to accurately fit together without danger of damage or slipping the gear 11 is preferably in the form of a plain cone constructed of any suitable material conducive to friction—such, for instance, as laminae of rawhide, as shown in Fig. 4—surrounding a spool 12 and clamped together at each end by the plates 13 14, the spool being mounted upon a stud shaft or pin 15, and the gears 9 10 have plain surfaces, with which the rawhide cone 11 engages. Another advantage in utilizing plain friction-gears for this purpose is that when the cone 11 is moved inwardly for forcing the clutch members 7 8 asunder the friction of such cone against the gear 9 is insufficient to cause damage or to interfere with the direct rotation of the propeller-shaft until it has been forced inwardly a sufficient distance to crowd the clutch members 7 8 apart, whereupon the direct connection between the shafts is broken and the motion of the propeller-shaft is reversed and continued through the intermediary of the gears 9 10 11, which gears constitute the convertible gear herein referred to.

The friction cone or gear 11 is preferably supported by the motor-shaft 6, and it is moved into and out of engagement with the gears 9 10 by the same movements which force the clutch members 7 8 toward and from each other. In accomplishing this I employ a shell or casing consisting of two members 16 17, divided horizontally and fitted together, so as to incase the gears and clutch members, and in the upper one of these shell-sections is mounted the stud-shaft 25, which carries the gear 11. These shell members 16 17 are provided at each end with perforated ears or lugs 18 19, respectively, the latter of which are bolted or riveted together, while the others are pierced by an I-screw 20, held by a pair of jam-nuts 21, and pivoted at its lower end to a hinged standard 22, whose lower end is

secured in any suitable manner to the bottom of the boat or other support, the purpose of the I-screw 20 and jam-nuts 21 being to hold the sections of the shell together and at the same time adjust the angularity of the stud-shaft 15 with reference to the horizontal, for the purpose hereinafter explained. Mounted loosely upon each of the shafts 2 6 is an eccentric 23 24, respectively, upon which the shell 16 17 is journaled, each section of the shell being provided on each side with a semi-circular collar 25, and these semicircular collars being fitted together around each of the eccentrics 23 and 24 constitute the bearing in which the eccentrics turn and by which the shell is supported. These eccentrics 23 24 are arranged concentrically with each other—that is, with their major portions on the same side of the shafts 2 6—and they are connected together so as to be rotated simultaneously by any suitable means—such, for instance, as a yoke 26, having each of its ends secured to one of the arms 27, formed on the eccentrics 23 24, respectively, such yoke being also given the form of a handle or lever 28, and consisting of a strip of flexible metal or material folded upon itself and secured together at its mid-length, so that its extremities may separate to permit the clutch members 7 8 to go and come. Thus it will be seen that when the lever 28 is thrown in one direction the gear 11 (assuming it to be elevated) will be forced downwardly between the gears 9 10 by virtue of the eccentrics carrying the upper half of the shell downwardly with reference to the shafts 2 6, the pivoted standard 22 in the meanwhile permitting the shell to make the necessary longitudinal movement to follow the action of the eccentrics. This motion forces the clutch members 7 8 apart and reverses the movement of the propeller-shaft, as before described. A reverse movement of the lever 28 will bring the wider portions of the eccentric on top of the shafts 2 6, and consequently carry the casing or shell upwardly and move the gear 11 out of contact with the gears 9 10. In order now that this latter movement of the lever 28 may also bring the clutch member 7 up to its work against the clutch member 8, I provide the inner ends of the collars 25 with one or more inclines 29, and upon the inner end of each of the eccentrics 23 I form a flange 30, whose vertical outer edge is also provided with a corresponding number of complementary inclines 31, fitting against the inclines on the inner ends of the collars 25. The inclines 29 on the collar 25 are arranged in pairs and diametrically opposite each other, so that the inclined portions will be out of parallel and project at an angle to each other, as more clearly illustrated in Fig. 5, and the inclines on the eccentrics 23 24 have a like arrangement, so that their prominent portions will fit into the depressed portions of the inclines 29. Thus it will be seen that should the lever 28 be thrown in the direction away from the observer, as viewed in Fig. 3,

the prominent portions of the inclines 31, wedging in between the prominent portions of the inclines 29 on the collars 25, would cause the shell 16 17 to move toward the motor or engine and would also cause the gear 9 and clutch member 7 to move toward and bring the latter into engagement with the clutch member 8. The instant the apexes of the teeth on the clutch members come into engagement and the rotation of the shaft 2 begins the resistance of the propeller will crowd the shaft 2 inwardly and force the teeth of the clutch members into complete engagement, even though the inclines 29 31 should be insufficient for this purpose. When the reversing-lever 28 is thrown in the opposite direction, the prominent portions of the inclines 31 on the eccentrics leave the prominent portions of the inclines 29 and come opposite the depressed portions of the latter inclines, and at the same time the eccentrics 23 24 carry the cone 11 downwardly and crowd it snugly between the gears 9 10, the shell 16 17 being permitted to move back away from the engine to its normal position, and thus allowing the cone 11 to center itself equally between the gears 9 and 10. In order that the axis of the gear 11 may pass directly through the axis of the shaft 6 when the gear is down between the gears 9 10 in its operative position, its stud-shaft 15 is set normally at a slight tangent to the shaft 6, as shown in Fig. 2, so that by the time it descends to its operative position it will have arrived into line with one of the diameters of the shaft 6.

It is of course evident that if the gears 9 10 were permitted to continue to move apart as long as the downward movement of the cone 11 continued such cone could never gain sufficient grip or friction to effectually transmit the motion. Therefore in order that the separating movement of the gears 9 10 may cease after the clutch members 7 8 have sufficiently separated and the cone 11 may continue downwardly, each of the inclines 29 31 is provided at its depressed portion with a short stretch 32 and at its prominent portion with a short stretch 33, whose planes are parallel with each other, and also with corresponding portions on the diametrically opposite incline, so that the prominent portion 33 of the incline on the eccentric will slide along the plain surface 32 at the depressed end of the incline 29 on the collar 25, and thus permit the lever 28 to continue its throw for a short distance, and consequently carry the eccentrics and cone 11 still farther downward without permitting any further separation of the gears 9 10, thereby enabling the operator to jam the cone 11 between such gears with sufficient force to transmit the motion before the movement of the lever 28 is checked by the precipitous portions 34 of the inclines coming into engagement.

Should the engineer find that the lever 28 when at the extremity of its stroke is in an inconvenient position, the same may be ad-

justed by raising or lowering one side of the shell 16 17 through the agency of the screw 20 and jam-nuts 21.

27^a is a stop on the arm 27 for limiting the throw of lever 28 in one direction.

Having thus described my invention, what I claim as new, and desire to secure by Letters Patent, is—

1. A device for the purpose described having in combination a motor-shaft, a driven shaft, direct gears detachably connecting said shafts together, gear-wheels connected to each of said shafts, a movable gear-wheel adapted to connect said gear-wheels together, a support mounted upon one of said shafts and carrying said movable gear-wheel, an eccentric for moving said support and carrying said movable gear-wheel into and out of engagement, and means for throwing said direct gears together, substantially as set forth.

2. A device for the purpose described having in combination a motor-shaft, a driven shaft, direct detachable gears connecting said shafts together, bevel-gears secured to said shafts respectively, a movable bevel or conical gear adapted to wedge between said bevel-gears, a support for said conical gear, an eccentric for moving said support, said support and eccentric being provided with engaging inclines for moving said direct gears into engagement, substantially as set forth.

3. A device for the purpose described having in combination a motor-shaft, a driven shaft detachably connected to said motor-shaft, a bevel-gear on each of said shafts, a movable cone adapted to be crowded between said bevel-gears, a support for said movable gear movable longitudinally and transversely of said shafts, and means for moving said support toward the shafts for crowding said movable gear between said bevel-gears and forcing said shafts apart, and means for forcing said shafts together when said support makes the reverse movement, substantially as set forth.

4. A device for the purpose described having in combination a motor-shaft, a driven shaft detachably connected to said motor-shaft, a bevel-gear on each of said shafts, a movable conical gear adapted to be crowded between said bevel-gears, an eccentric journaled on each of said shafts, a support for said conical gear journaled on said eccentrics and being provided with inclines, and inclines operated by said eccentrics and engaging with said first inclines for forcing said shafts together when the eccentrics throw said conical gear out of engagement, substantially as set forth.

5. A device for the purpose described having in combination a motor-shaft, a driven shaft detachably connected thereto, a bevel-gear on each of said shafts, a movable gear adapted to be crowded between said bevel-gears, means for throwing said movable gear into and out of engagement and inclines for throwing said shafts into engagement operating in unison with said means and being provided with

plain, straight or inactive surfaces whereby said movable gear may continue to crowd between said bevel-gears after the latter have reached the extremity of their separating 5 movement, substantially as set forth.

6. A device for the purpose described having in combination a motor-shaft, a driven shaft detachably connected thereto, a conical gear on each of said shafts, an eccentric journaled 10 on each of said shafts and having a circumferential flange provided with inclines on the side thereof, a movable gear adapted to be crowded between said bevel-gears, a support for said movable gear journaled upon said 15 eccentric and having inclines engaging with said first inclines and adapted to force one of said shafts and bevel-gears toward the other, said inclines being provided with plain surfaces 32, and a lever secured to said eccentric, substantially as set forth.

7. A device for the purpose described having in combination a motor-shaft, a driven shaft detachably connected to said motor-shaft, convertible gears also for connecting said 20 shafts together and being provided with a detachable member, a support for said detachable member supported upon said shafts, means for oscillating said support with reference to said shafts and means for adjusting 25

the normal position of said support with reference to said shafts, substantially as set forth. 30

8. A device for the purpose described having in combination a motor-shaft, a driven shaft detachably connected thereto, convertible gears also for connecting said shafts having 35 a detachable member, an eccentric on each of said shafts, a support for said detachable member journaled upon said eccentrics, and a flexible standard connected to one side of said support for limiting its rotation, substantially as set forth. 40

9. A device for the purpose described having in combination a motor-shaft, a driven shaft detachably connected thereto, convertible gears also for connecting said shafts together 45 having a detachable member, a support for said detachable member, the axis of said detachable member being arranged normally out of line with the center of said shafts, means for moving said support toward said shafts 50 and carrying the axis of said detachable member into line with the center of said shafts and forcing said shafts apart, substantially as set forth.
